TOY

John H. Dawson, Rockville, Md.

Application June 14, 1940, Serial No. 340,592

7 Claims. (Cl. 46—81)

This invention relates to toys and more particularly to traction toys which are adapted to be constructed to simulate an airplane carrier and provided with means for launching in succession a plurality of glider elements, thus creating the effect of such a ship in action.

The object of the invention is to provide a toy of the character indicated, of simple and robust construction, capable of economical manufacture, and embodying details of construction assuring accurate and effective operation to produce the effect desired.

The invention consists in the novel construction, arrangement and combinations of parts herein-after more particularly described and claimed.

One sheet of drawings accompanies this specification as part thereof, in which like reference characters indicate like parts throughout.

Figure 1 is a plan view of one embodiment of the invention;

Figure 2 is a vertical longitudinal cross-section showing details of construction;

Figure 3 is an enlarged fragmentary portion of Figure 2; and

Figure 4 is an enlarged fragmentary portion of Figure 1.

In accordance with the present invention, a platform 1 is provided, which may be of rectangular shape as is customary on airplane carriers. Depending from the platform 1 is a body part 2, shown herein as simulating the hull of a vessel.

At spaced intervals on the platform 1 are fore and aft slots 3, defining what are herein-after referred to generally as glider stations. As illustrated, there are two glider stations substantially amidships and one station aft. Obviously more or less stations can be provided depending on the size of the particular toy, and such stations can be either arranged in alignment or staggered as may be desired.

Preferably such stations as are located aft of other stations, are located on slight elevations from the platform in which connection the platform can be raised, as indicated at 4, to assure the rear gliders being launched above the forward gliders regardless what the order of discharge and thus avoiding the necessity of more complicated mechanism to assure such elevation. Alternatively, if desired, the rear gliders wings could be set at proper inclination to assure a sharper ascent, or the rear platform 4 could be set at an inclination.

To simulate gun turrets, circular housings 5 may be struck from the platform adjacent each

station slot and extending on either side thereof, and such housings may be provided with hook members 6 struck inwardly from the opposite sides thereof to provide anchoring means for the ends of the glider propeller element 7, which may be a coiled spring, as illustrated, or other suitable elastic element. By this arrangement it may be noted that the spring 7 extends directly across the slot 3 substantially midway thereof, and each of the slots 3 are further bridged adjacent the rear end by a member 8.

A plurality of glider elements are provided, each of which includes a longitudinal fuselage member 9, winged members 10, and tail members 11. Each fuselage member 9 is notched forwardly as at 12 to engage the resilient propelling member 7, and similarly notched adjacent its rear end as at 13 to engage the bridge member 8.

It will be apparent from this description that each glider element can be engaged with the platform at a station by catching the notch 12 over the spring 7 with the fuselage member 9 in slot 3 and then drawing the glider element rearwardly, tensioning spring member 7, until the notch 13 engages the bridge member 8.

The housing 2 carries near its forward end a transverse axle 15 upon which are mounted forward traction wheels 14 within the housing, supporting the forward end of the toy.

Also within the housing 2 and adjacent the rear end thereof and depending from the platform 1, is a spring motor 16 of any suitable construction, having a driving shaft 17 extending transversely of the housing. This driving shaft 17 carries a gear 18 which meshes with suitable gears 19 and drives cam gears 20 arranged on transverse shafts 22 journaled in the housing of the spring motor, or otherwise as desired. As illustrated herein, the rear cam gear 20 has a cam element 21 attached directly thereto in alignment with the rear glider station slot 3, while the forward cam gear is fixedly secured to its shaft 22, upon which shaft are fixedly secured the cam fingers 21' each in alignment with its respective station slot.

The rear traction wheels 25 are mounted directly on the drive shaft 17 of the spring motor, one on either side thereof, and the motor is provided with a winding key 24 which extends through the side of the housing 2 by means of which the motor can be wound.

In operation the various glider elements will be secured in the respective station slots as previously described and the spring motor wound by means of key 24 while the operator holds one of

the traction wheels 25. The toy will then be placed upon the floor and released, whereupon it will proceed to move forward and as the cam members 21 and 21' successively pass through their respective station slots they will each lift the rear end of the fuselage member 9 of its glider from its retaining bridge member 8 to permit the resilient spring 7 to project the glider forwardly into flight. It will be noted that by positioning the fuselage members 9 in the slots 3 the gliders will be effectively guided laterally in launching and by elevating the rearward glider stations with respect to those in advance thereof it is immaterial whether the forward gliders are first launched or not as the rear gliders will rise above the forward gliders in any event.

Various modifications will readily suggest themselves to those skilled in the art but within the scope of the present invention as claimed.

I claim:

1. A toy, comprising a platform, traction means for the platform, a launching station on the platform, a glider element, means at the launching station cooperating with the glider to hold the latter in position, means at the launching station for propelling the glider into flight and means coordinated with the traction means for rendering operative the propelling means.

2. The structure of claim 1 in which the glider holding means includes a detent and catch.

3. The structure of claim 1 in which the glider propelling means includes a resilient member secured to the platform and means on the glider for engaging said resilient member.

4. The structure of claim 1 in which the launching station includes a slot in the platform, the holding means includes a transverse bridge member adjacent one end of the slot and ex-

tending transversely thereof, the propelling means comprises a resilient member extending transversely across the slot and anchored to the platform on opposite sides of the slot in which the glider includes a longitudinal fuselage member having means for engaging said bridge member and the tensioned resilient member with cam means arranged to lift and disengage the fuselage from the bridge member.

5. In combination in a toy, a platform, traction means for the platform, a plurality of glider launching stations on the platform, a glider member for each station, means for independently securing each glider to its station, independent glider propelling means at each station and means operated by the traction means for releasing the gliders at predetermined intervals.

6. In combination in a toy, a platform, traction means for the platform, a plurality of glider launching stations on the platform some of said

20 stations in advance of others, the rear stations elevated with respect to those forward of them, gliders, one for each station, means for positioning each glider on its station, means for projecting each glider into flight from its station and means operated by the traction means for releasing the gliders in predetermined sequence.

7. In combination in a toy, a platform, traction means for the platform, a plurality of glider stations on the platform some of said stations in advance of others, gliders one for each station, means for positioning each glider on its station, means controlling the launching inclination of the respective gliders, means for projecting each 30 glider into flight from its station and means operated by the traction means for releasing the gliders in predetermined sequence.

JOHN H. DAWSON.
